UNITED STATES PATENT OFFICE.

WILLIAM J. KLEMM, OF CHICAGO, ILLINOIS, ASSIGNOR TO JOHN A. KNISELY, OF CHICAGO, ILLINOIS.

METAL WINDOW-FRAME.

SPECIFICATION forming part of Letters Patent No. 742,999, dated November 3, 1903.

Application filed October 2, 1902. Serial No. 125,640. (No model.)

To all whom it may concern:

Be it known that I, WILLIAM J. KLEMM, a citizen of the United States, residing at Chicago, in the county of Cook and State of Illinois, have invented certain new and useful Improvements in Metal Window-Frames, of which the following is a specification.

My invention relates to improvements in means for providing access to the sash-weights in a sheet-metal window-frame for the purpose of detaching, attaching, or adjusting the sash-chains connected with such weights.

The improvements embodied in my invention, consisting of pockets or openings cut in the frame and a cover or closure for such openings, are illustrated in the accompanying drawings, which form a part of this application, and are described in detail in the specification following.

In the drawings, Figure 1 shows in elevation the lower portion of a window-frame with sections broken away to show the application of the closure, in normal position and when being removed. Fig. 2 is a perspective view of the lower portion of a sheet-metal frame of common form with the closure applied thereto. Fig. 3 is a cross-section of the window-frame at a point just above the closure. Fig. 4 is a detail view showing in side elevation the closure, and Fig. 5 is a vertical section taken through the inner face of the window-frame and showing in elevation the weight.

Referring to the details of the drawings, A represents a sheet-metal window-frame of common form, provided with sash-weight boxes a' and slideways or grooves a^2 for the sash, the latter not being shown, as they form no part of my invention and may be of any desired construction. Near the sill and near the head of the frame I cut openings b in the inner or sash side of the frame, through which access may be had to the weight-boxes. The edges of the metal at the sides and bottom of the openings are bent inwardly, as at b' and b^2 ; but the edge at the top of the opening is left in the same plane with the rest of the face of the frame, as shown, or, if desired, may be given a slight outward bend. The closure for the opening consists of a

strip of sheet metal of the same thickness as that of which the frame is composed, cut slightly larger than the opening and has its upper end bent inwardly, as at c' . The sides 55 of the strip are bent at right angles to the body of the strip, forming flanges c^2 , each of which is bent upon itself to form a groove c^3 of sufficient size to receive the bent edge of the frame at the sides of the openings, as shown 60 clearly in Fig. 3. The lip c^4 at the lower end of the strip is left in its normal plane and is adapted to fit the depression formed by the inward bend b^2 of the edge of the frame adjacent to the bottom of the opening. 65

The closure C, formed as above described, is fitted to the opening in the frame by inserting the end c' under the upper edge of the opening b , then pushing the closure toward the frame, whereupon the edges b' will enter 70 the grooves c^3 and the lower lip c^4 will be seated in the depression formed by the inward bend b^2 , thus bringing the outer faces of the closure c' flush with the adjacent portions of the frame both in the sash slideways and 75 in the face of the frame. It will be understood that the grooves c^3 are so proportioned that the edges of the frame will fit tightly therein, thus giving sufficient frictional engagement to retain the closure in place under all normal conditions. If it be desired to remove the closure, the end of a screwdriver or similar tool inserted along the edge of the flanges c^2 in the slideways will be sufficient to force the closure outwardly until it 80 may be grasped by the hand.

Though I have shown the closures only at the bottom of the frame, it will be apparent that the same device may be applied near the head of the frame. 90

It will be seen that, constructed and arranged as shown, the exposed surface of the closure and that upon which the sash slides as it is moved up and down, is in the same general plane with the adjacent surface of 95 the frame, thus offering no obstruction to the free movement of the sash.

In considering the utility of my invention it should be borne in mind that the closure does not mar or disfigure the appearance of 100 the frame, does not require any catches or locks to secure it in place, is quickly and

easily applied and removed, and is so simple that it is cheaply manufactured.

Having thus described my invention, what I claim as new, and desire to secure by Letters 5 Patent, is—

1. In a window-frame having openings therein to afford access to the weight-boxes, the edges adjacent to the openings being recessed substantially as shown, closures for 10 said openings having portions fitting said recesses and adapted to frictionally embrace the edges of the frame adjacent to the openings.
2. In a window-frame having weight-box 15 openings therein, and with the edges at the sides and bottom of said openings bent inwardly, removable closures for said openings having portions overlapping said inwardly-bent portions at the bottom and sides of the 20 weight-box openings, said closure also having a portion underlying the edge of the frame at the top of said opening.
3. In a window-frame having weight-box 25 openings therein, removable closures for said openings, consisting of metal plates having grooves formed in their side edges adapted to receive the edges of the frame adjacent to

the sides of said openings, said plates also having an upwardly-projecting tongue at their upper edge and a downwardly-projecting 30 tongue at their lower edge, substantially in the manner and for the purpose described.

4. In a window-frame having weight-box openings therein, the edges of the frame at the sides and bottom of said openings being 35 bent inwardly as shown, closures fitting said openings, and having portions fitting said recesses, and adapted to frictionally embrace the edges of the frame at the sides of said openings, substantially as set forth. 40

5. A closure for weight-box openings in a window-frame, consisting of a strip of metal having an inwardly-bent lip at one end, and having its side edges bent inwardly at right angles to form flanges and having said flanges 45 bent upon themselves to form grooves to receive the edges of the frame adjacent to said openings.

In testimony whereof I affix my signature in presence of two witnesses.

WILLIAM J. KLEMM.
